(57) **CLAIM**

The ornamental design for an ornamental rolling convertible workstation as shown and described.

DESCRIPTION

FIG. 1 is a side/front perspective view of an ornamental rolling convertible workstation showing our new design; FIG. 2 is a side/back perspective view of an ornamental rolling convertible workstation showing our new design with handle extended;

FIG. 3 is a perspective view of an ornamental rolling convertible workstation showing our new design with worksurface and light extended;

FIG. 4 is a perspective view of an ornamental rolling convertible workstation from an approximately 90° direction of that shown in FIG. 3 showing our new design with worksurface, cell phone holder, connection box, and electrical cord extended;

FIG. 5 is a perspective view of an ornamental rolling convertible workstation from an approximately similar direction of that shown in FIG. 4 showing our new design with light and printer/scanner components extended;

FIG. 6 is a perspective view of an ornamental rolling convertible workstation from an approximately similar direction of that shown in FIG. 5 showing our new design with light and drawers extended;

FIG. 7 is a perspective view of an ornamental rolling convertible workstation from an approximately similar direction of that shown in FIG. 6 showing our new design with light and drawer extended;

FIG. 8 is a top view of an ornamental rolling convertible workstation showing our new design;

(Continued)

FIG. 9 is a top view of an ornamental rolling convertible workstation in the same view as shown in FIG. 8 showing our new design with components extended;

FIG. 10 is a bottom view of an ornamental rolling convertible workstation opposite the top view shown in FIG. 8 showing our new design;

FIG. 11 is a bottom view of an ornamental rolling convertible workstation in the same view as shown in FIG. 10 showing our new design with components extended;

FIG. 12 is a front view of an ornamental rolling convertible workstation showing our new design;

FIG. 13 is a front view of an ornamental rolling convertible workstation in the same view as shown in FIG. 12 showing our new design with components extended;

FIG. 14 is a back view of an ornamental rolling convertible workstation opposite the front view shown in FIG. 12 showing our new design;

FIG. 15 is a back view of an ornamental rolling convertible workstation in the same view as shown in FIG. 14 showing our new design with components extended;

FIG. 16 is a side view of an ornamental rolling convertible workstation showing our new design;

FIG. 17 is a side view of an ornamental rolling convertible workstation in the same view as shown in FIG. 16 showing our new design with components extended;

FIG. 18 is a side view of an ornamental rolling convertible workstation opposite the side view shown in FIG. 16 showing our new design; and,

FIG. 19 is a side view of an ornamental rolling convertible workstation in the same view as shown in FIG. 18 showing our new design with components extended.

Any features shown with broken lines are for environmental purposes only and form no part of the claimed design. The

design shown is not to be limited to any particular size and may be scaled larger or smaller.
